NECKTIE MACHINE

Max M. Newman, New York, N. Y., assignor to
 American Machine & Foundry Company, a
 corporation of New Jersey

Application December 30, 1942, Serial No. 470,596

2 Claims. (Cl. 112—136)

1

This invention relates to necktie sewing machines, more particularly to improvements in the lining guiding mechanism thereof. One of the objects of the invention is to provide a lining guiding mechanism for the type of necktie whose fabric edges are stitched together while the folded fabric is inside out, and having what is commonly called a side seam, that is a stitch line which extends inwardly from either end of the fabric in a direction away from the overlapped fabric edges and toward the fold line, to a point at the neck band portion of the fabric. To this end, there is provided in the particular embodiment of the invention exemplified herein, a fabric guide which engages the fold line and is displaced transversely thereof in properly timed relation to the feeding of the fabric to the stitch former to produce the desired side seam type of stitch line extending longitudinally of the overlapped fabric edges.

Another object of the invention is to produce the type of stitch line required for the so called "small knot" tie wherein the stitch line has a narrow knot forming portion adjacent the neck band portion thereof. For this purpose the lining guiding mechanism is constructed so that its operation may be varied to produce a stitch line which is mainly parallel to the fabric edges except at the knot forming portion where it has a re-entrant portion as required for a small knot.

Still another object is to provide a sewing machine wherein either a side seam or "small knot" type of stitch line may be obtained by varying the operation of the machine.

With these and other objects not specifically mentioned in view, the invention consists in certain constructions and combinations hereinafter fully described and then specifically set forth in the appended claims.

In the accompanying drawings, which form a part of this specification and in which like characters of reference indicate the same or like parts:

Fig. 1 is an end elevation of the improved machine;

Fig. 2 is a side elevation from the line 2—2 of Fig. 1;

Fig. 3 is a development of the portion of the pattern band used for forming a stitch line of the side seam type, the screws retaining the pieces of the pattern band being omitted;

Fig. 4 is a development of the complete pattern band;

Fig. 5 is a side elevation of the same;

Fig. 6 is a plan view of a folded necktie fabric illustrating the stitch line produced by engage-

2

ment of the fabric guide with the fold line of the tie fabric;

Fig. 7 is a plan view of a necktie fabric illustrating the stitch line produced by engagement of the guide with the raw edges of the tie fabric;

Fig. 8 is a section on line 8—8 of Fig. 6; and

Fig. 9 is a section on line 9—9 of Fig. 7.

The stitch-forming mechanism illustrated in this invention is of the same type and construction disclosed in the co-pending application of J. A. Neumair, Serial No. 441,464, filed May 2, 1942, for Lining guide cam, on which Patent No. 2,372,224 was issued March 27, 1945. With the stitch-forming and feeding mechanism shown herein in which a folded tie fabric is engaged by suitable crimpler bars 10 and 12, which are supported by endless sprocket chains 95 and 96, the bars 10 and 12 are suitably beveled as shown in said Neumair patent, to provide triangular teeth 11 and 13 (Fig. 2). The bars 10 and 12 interengage with each other and advance and pleat the fabric upon a needle 14 carrying a thread 16 extending along the needle and through the eye 25 thereof into position to be grasped by the operator. In this manner the necktie fabric is stitched; and when it is desired to withdraw it from the needle, the operator holds the projecting end of the thread firmly to the tie fabric and reverses the 30 direction of rotation of the machine, thereby backing the stitched fabric off the needle. Since the construction of the needle is the same as shown in said Neumair patent, further description thereof is deemed unnecessary.

Referring to Fig. 1, in my construction there is provided a fabric guide 18 suitably located above table 20 upon which the necktie fabric is positioned preparatory to inserting its leading end between the bars 10 and 12. Guide 18 has an upright flange 22 on its outer end arranged to engage and guide the superposed longitudinal edges of the tie fabric in predetermined relation to the point of the needle, and is also provided with a horizontal blade 24 adapted to engage the interior 40 of the fold line of the fabric and thereby maintain the fabric in predetermined relation to the point of the needle.

Guide 18 is adjustably mounted in sleeve 26 which is split at one end and carries a clamping 50 collar 28 provided with a thumb screw 30 for clamping said split end to guide 18. Sleeve 26 slides in a bearing 32 of frame 136 and is connected to a rod 34 by means of a yoke 36 which has a notch at each end wherein sleeve 26 and rod 34 are positioned and clamped by screws 38.

and 40 respectively. The yoke 36 has an extension 41 whereon a latch 42 is pivoted by a cap screw 44. Fig. 1 shows latch 42 in two positions, the active position as shown in full lines and used when sewing a "small knot" tie, and the inactive position as shown in dotted lines. The rod 34 (Fig. 1) is slidably mounted in bearings 46 and 48 of frames 49 and 136, respectively, and is urged towards the left by means of an adjustable collar 50 fastened on rod 34 by a screw 52 and a compression spring 54 seated against bearing 48. A fork 56 is threaded on one end of rod 34 against a counter nut 58 also threaded thereon. A pin 60 which is secured in the fork 56, engages a finger 61 on a cam lever 62 which is disposed between the bifurcations of fork 56 and pivoted in a slot 63 formed in the outer end of member 64 by a pin 66. A cam roller 68 mounted on a pin 70 secured in lever 62 engages the edge of a fabric pattern band hereinafter described. The member 64 is secured by a screw 72 to a stationary shaft 74, and it also acts as a collar to retain a wheel 76 loosely mounted on this shaft. To the spokes 77 of wheel 76 a ring 78 is clamped by two bars 80 secured to the spokes by screws 82. On the periphery of ring 78 are secured a number of cam pieces, constituting a fabric pattern band, as will be described later.

Bosses 83 are formed on the spokes of wheel 76, and to these bosses a gear 84 is fastened by screws 86, gear 84 meshing with and being driven by a gear 88 fastened by a screw 90 to the end of a shaft 92 which protrudes from frame 136. The inner end of shaft 92 carries a sprocket 94 which is driven by the sprocket chain 95 to which the above mentioned crimpler bars 12 are secured. Sprocket chain 96 runs over a sprocket 97 supported on a stud in frame 136, and the crimpler bars 13 are secured to chain 96. Both sprocket chains 95 and 96 are driven by suitable mechanism (not shown).

Fig. 6 shows a tie fabric 98 with its longitudinal edges folded upon each other. The heavy dotted line 100 indicates the line of stitching often used in ties which have no lining. Starting close to the raw edges of the fabric at a point 102 near the leading end thereof, the stitch line extends inwardly, gradually widening the unstitched margin until a point 104 in the neck band portion of the fabric is reached, whence the line of stitch extends outwardly to provide a gradually narrowing margin up to a point 106 close to the raw edges where the stitch line ends. The blade 24 of guide 18 is shown engaging the interior of the fold line of the fabric, thereby serving to guide the fabric as it is fed upon the needle by the engagement of crimpler bars 10 and 12. The required movement of the guide 18 as it guides the tie fabric to produce the line of stitch 102, 104, 106 is effected through the previously mentioned fabric pattern band which consists of five cam pieces 108, 110, 112, 114 and 116. These pieces are fastened to ring 78 together with two additional cam pieces 126 and 128, by cap screws 118; washers 120 and nuts 122; the screws 118 passing through transverse elongated slots 124 of ring 78. The development of these five cam pieces is shown in Fig. 3 and in Fig. 4 with the pieces 126 and 128. The cam pieces 126 and 128 are moved backwardly against the spokes 77, when the side seam stitch line shown in Fig. 6 is desired, so that their outer edges lie inside of the outer edges of the pieces 110 and 112; and the latch 42 is thrown to the inactive position indicated in Fig. 1. The screw 118 con-

necting the pieces 108 and 116 passes through coinciding circular holes 136 formed in the overlapping ends of these pieces. The overlapping ends of pieces 108 and 110 are provided with elongated longitudinal slots 137 and 138 respectively, through which the screw 118 connecting them passes. At the overlapping ends of pieces 110 and 112, the screw 118 passes through a circular hole 139 formed in the piece 110 and an elongated longitudinal slot 140 formed in the piece 112. The screw 118 connecting pieces 112 and 114 passes through a circular hole 139a in piece 114 and an elongated slot 140a in the piece 112. The screw 118 connecting pieces 114 and 116 passes through an elongated longitudinal slot 137a in piece 114 and a similar slot 138a in piece 116.

When the type of stitch shown in Fig. 7 is required the cam pieces 126 and 128 are slid outwardly into the position shown in Fig. 4, the nuts 122 on the screws 118 retaining the same being loosened to permit this movement of cam pieces 126 and 128. One end of piece 126 is provided with an elongated transverse slot 141 through which the corresponding screw 118 passes, the overlapped ends of pieces 126 and 128 being provided with coinciding transverse elongated slots 142 through which the screw 118 connecting them passes, and the screw 118 connecting piece 128 to piece 112 passes through a circular hole in piece 128 coinciding with a circular hole 143 in piece 112.

In the operation of the machine to produce the type of stitch line of Fig. 6, the machine is operated through a reversing clutch (not shown) similar to that disclosed in the Newman et al. Patent 2,387,282, issued October 23, 1945, to turn the shaft 74 and bring the mid-portion of cam piece 116 into engagement with cam roller 68. Then as the ring 78 rotates in a counterclockwise direction, the leading end of the fabric having been inserted and gripped between adjoining bars 10 as the same move around the sprocket 97, the point 102 of the fabric of Fig. 6 is impaled upon the needle 14 and the stitch line is begun. The operator holds the fabric taut by its trailing end and maintains the interior of the fold line against the outer end of the blade 24 as the guide 18 is displaced toward the longitudinal edges of the fabric as the roller 68 successively rides over the edges of the cam pieces 108 and 110. Thus the stitch line is formed progressively closer to the fold line until the point 104 of the fabric of Fig. 6 is reached, corresponding to the point 112a of cam piece 112. From point 112a the roller 68 is displaced toward the fold line of the fabric until the roller returns to its initial position at the mid-portion of cam piece 116. Thus the blade 24 is sufficiently displaced toward the fold line, so the line of stitching gradually approaches the fabric edges, from point 104 to point 106 of Fig. 6. The machine is then reversed to back off the stitched fabric from the needle.

The form of tie 130 as exemplified in Fig. 7 is sometimes referred to as a "small knot tie." The stitch line 132 is mainly parallel to the raw edges of the fabric, but has a re-entrant portion 134 which provides a narrow width for a small knot adjacent the neck band of the finished tie. For this purpose the upright flange 22 of guide 18 is utilized to guide the overlapped raw edges of the folded tie fabric 130, as shown in Fig. 7. To produce this line of stitching, the latch 42 referred to previously is thrown into its active position shown in full lines in Fig. 1. The machine

is then rotated to a point where the latch 42 comes to rest against the frame 136. Now the guide 18 is adjusted so that the distance of the flange 22 from the point of the needle 14 corresponds with the distance "A" of Fig. 7, from the fabric edges to the parallel portions of the stitch line. The re-entrant portion 134 of the stitch line is effected by the cam pieces 126 and 128 through the mechanism previously described.

The latch 42 maintains the roller 68 out of engagement with cam pieces 116 and 108 as wheel 76 revolves in a counter-clockwise direction and thereby prevents displacement of the guide 18 and causes the stitching to be formed in parallelism to the fabric edges along the leading end of the fabric, until the roller 68 engages cam piece 126. Then the fabric guide is displaced outwardly, as the roller 68 runs over the outwardly extending edge portion of the cam piece 126 on to the edge portion of cam piece 125 aligned with the adjoining edge portion of cam piece 128. In this manner the inwardly extending section of the re-entrant portion of the stitch line is formed, the operator tautly holding the fabric edges against the flange 22. As the roller 68 rides over the aligned edge portions of cam pieces 126 and 128, the parallel section of the re-entrant portion of the stitch line is formed, since the fabric guide is maintained stationary. As the roller 68 follows the outwardly extending edge portion of cam piece 128 at the trailing end of the latter, the fabric guide is moved toward the fabric edges to produce the outwardly extending section of the re-entrant portion of the stitch, as the operator holds the fabric edges against the flange 22. Then the latch 42 reengages the frame 136, and the parallel portion of the stitch line along the trailing end of the fabric is formed.

To vary the bowing of the side seam type of stitch line shown in Fig. 6, the cam piece 108 may be swung outwardly about the screw 118 connecting it to the piece 116, after unloosening this screw and the screw connecting pieces 108 and 110, and the pieces 110 and 114 may be similarly adjusted, the piece 112 being moved outwardly transversely to the extent required.

It will be noted that the lining guides 146 and 159, which underlie the L-shaped slot 151 in the table 20 and serve to guide a lining inserted into said slot by engagement with its edges, do not assist in the stitching of the unlined types of ties described above. For this reason and the further reason that their construction and operation is described in the above mentioned Neumair patent, further description thereof is omitted herein. However it may be noted that the lining guides 146 and 159 are supported by separate rods 144 and 157 which are slidably supported in frame 136, the rod 157 carrying a block 155 supporting a cam roller 153 which engages one edge of the cam pieces secured to the rim of wheel 76. The rod 144 carries a similar block (Fig. 2) provided with a cam roller engaging the other edge of said cam pieces.

It should be understood, however, that some types of "small knot" ties may be provided with a lining, and in this case the lining guides will serve to maintain the lining in a predetermined position with respect to the stitch line. While I have described my invention in its preferred forms, I desire it to be understood that modifications may be made and that no limitations upon the invention are intended than are imposed by the scope of the appended claims.

What is claimed is:

1. In a sewing machine for sewing together the overlapped longitudinal edges of a fabric, the combination with stitch-forming and feeding mechanism, of means operating in timed relation to the operation of said mechanism for guiding the fabric to form a stitch line of the side seam type, said means including a fabric guide arranged to engage the interior of the fold line of the fabric, and a pattern band, said pattern band including a rotary member revolving about a horizontal axis extending transversely of the fabric, a set of cam pieces secured on the periphery of said member, and said means also including a cam follower connected to said guide and engaging one edge of the cam pieces, and a device urging said follower against said edge of the cam pieces, said cam pieces having a predetermined configuration for displacing said guide transversely of the fabric to produce a side seam stitch line extending inwardly along the fabric edges in a direction toward the fold line from a point adjacent the leading end of the fabric to a point intermediate the fabric ends, and thence extending outwardly along the fabric edges in a direction toward the trailing end of the fabric, said cam pieces including a stationary cam piece, a cam piece movable axially of said rotary member, a cam piece pivotally connected at one end to said stationary cam piece and movably connected to said axially movable cam piece, and a pair of cam pieces movably connected to each other, one cam piece of said pair being pivotally connected to said stationary cam piece and the other cam piece of said pair being movably connected to said axially movable cam piece whereby said pivoted cam pieces may be swung outwardly on their pivotal connections and said movable cam pieces may be moved outwardly to permit various shapes of side seams to be obtained.

2. In a sewing machine for sewing together the longitudinal edges of a tie fabric which has been longitudinally folded along a curved fold line with its cut edges overlapped upon each other, the width of said folded fabric tapering from relatively wide end portions to a relatively narrow intermediate neck band portion, the combination with mechanism for feeding the folded fabric longitudinally and stitching its overlapped edges together, of a guide movable transversely of the folded fabric and arranged to engage the fold line of a folded fabric being fed by said mechanism, a rotary support revoluble about a horizontal axis extending transversely of the folded fabric being fed by said mechanism, a series of cam pieces having their ends overlapping one another and secured on the periphery of said rotary support, a cam follower mounted on said guide and arranged to engage one edge of said cam pieces as said pattern band is revolved, yielding means for maintaining said cam follower in engagement with said cam pieces, the edges of said cam pieces which engage said cam follower having a predetermined configuration to cause said guide to be displaced transversely across the folded fabric while engaging the fold line of the fabric being fed by said mechanism and thereby permit said fabric to be displaced transversely to produce a stitch line of the side seam type wherein the stitch line extends inwardly and longitudinally along the overlapped fabric edges from the leading end of said fabric to a point within said neck band portion thereof and thence outwardly and longitudinally along the overlapped fabric edges toward the trailing

end of said fabric, said cam pieces having aligned perforations in the overlapping portions at the ends of the cam pieces, and members extending through said perforations and releasably secured to said rotary support to retain the cam pieces to said rotary support whereby upon releasing said members from said rotary support said cam pieces may be adjusted axially of said rotary support to permit variation of the displacement of said guide while engaging the fold line of a fabric being fed by said mechanism and thereby vary the shape of the stitch line formed along the overlapped edges of said fabric.
